(57) **CLAIM**

The ornamental design for a tray table for supporting an electronic device, as shown and described.

DESCRIPTION

FIG. 1 is a front perspective view of a tray table for supporting an electronic device, of which the tablet device shown in broken lines is for illustrative purposes only and forms no part of the claimed design.

FIG. 2 is a back perspective view of a tray table for supporting an electronic device, of which the tablet device shown in broken lines is for illustrative purposes only and forms no part of the claimed design.

FIG. 3 is a front view of a tray table for supporting an electronic device.

FIG. 4 is a back view of a tray table for supporting an electronic device.

FIG. 5 is a left view of a tray table for supporting an electronic device.

FIG. 6 is a right view of a tray table for supporting an electronic device.

FIG. 7 is a top view of a tray table for supporting an electronic device.

FIG. 8 is a bottom view of a tray table for supporting an electronic device, the broken lines of which are shown for illustrative purposes only and form no part of the claimed design.

FIG. 9 is a left cross section view taken along line A of FIG. 3 showing an hourglass shaped groove for accepting an electronic device and bottom opening of a tray table for supporting an electronic device; and,

FIG. 10 is a right cross section view taken along line A of FIG. 3 showing an hourglass shaped groove for accepting an electronic device and bottom opening of a tray table for supporting an electronic device.
